ROSCOE W. STEPHENS, OF LOS ANGELES, AND CHARLES E. WILCOX, OF ANAHEIM, CALIFORNIA, ASSIGNEES OF ONE-FOURTH TO CHARLES DRADER, OF BEVERLY, CALIFORNIA, AND ONE-FOURTH TO EARL W. BAILEY, OF BAKERSFIELD, CALIFORNIA

PUMP AND METHOD OF PACKING THE SAME

Application filed July 16, 1927. Serial No. 206,311.

Our invention relates to reciprocating pumps, and has a particular utility in the oil well industry in which connection it will be described in this application for Letters Patent.

In the oil well industry, oil is lifted to the surface of the ground by means of a reciprocating pump located near the bottom part of the well, this pump having a barrel which is connected to an oil tube, and a plunger which is reciprocated in the barrel by a string of sucker rods.

In certain wells the oil carries sand or other foreign matter which works in between the barrel and the plunger and acts as an abrasive to wear out the pump parts.

It is one of the objects of this invention to provide a pump in which sand or other abrasives will be precluded from entering the space between the plunger and the barrel.

Our invention consists of a pump having means for introducing a comparatively heavy lubricant or other suitable abrasive excluding medium into the minute space between the plunger and the barrel. We have found that best results may be obtained when the lubricant is under greater pressure than the pressure of the fluid at the top of the plunger, so that there will be a very slight but positive flow of abrasive excluding medium through the space between the plunger and barrel.

It is accordingly another object of this invention to provide a pump in which there is a slight but positive flow of abrasive excluding medium through the space between the barrel and plunger of the pump.

Other objects and advantages of the invention will be pointed out in the following description.

Referring to the accompanying drawings in which the invention is illustrated:

Fig. 1 is a vertical section through one form of the invention.

Fig. 2 is an enlarged fragmentary section showing a plunger of the invention.

Fig. 3 is a section taken on the line 3—3 of Fig. 1.

Fig. 4 is a vertical section through another form of the invention.

Figs. 5 to 8 inclusive are sections taken on the lines 5—5, 6—6, 7—7, and 8—8 of Fig. 4.

Referring to Figs. 1 to 3 inclusive in which one form of the invention is illustrated, the numeral 11 represents a pump barrel, this 55 pump barrel having a liner 12. The lower end of the pump barrel is secured to a foot piece 13 in which a standing valve 14 is seated. The upper end of the barrel 11 is secured, as shown, to a head 16, this head 16 having 60 means whereby an oil tube 17 may be connected to the pump. Adapted to reciprocate in the barrel 11 is a plunger 18 having a working valve or traveling valve 19. The upper end of the plunger 18 is connected to the lower 65 end of a string of sucker rods 20 which extends upward through the oil tube 17 to the surface of the ground whereat it is connected to a suitable reciprocating means.

Surrounding the upper part of the barrel 70 11 is a jacket 22. The lower end of the jacket 22 is secured to the barrel 11 by a flange portion 23, and the upper end thereof is threadedly secured at 24 to the head 16. The jacket 22 provides an annular reservoir 26 which 75 surrounds the upper part of the barrel 11. The lower end of the reservoir 26 is connected by a plurality of openings 28 to the minute space which exists between the barrel 11 and the plunger 18. The upper end of the reservoir 26 is connected by a plurality of openings 29 to the space above the plunger 18. The reservoir 26 contains a body 30 of abrasive excluding medium. This abrasive excluding 80 medium is preferably in the form of a heavy lubricant having a specific gravity greater than that of the liquid being pumped by the reciprocating pump of the invention.

As illustrated best in Fig. 2, a plunger 34 is 85 placed in the reservoir 26 and forces downward on the top of the body 30. The plunger 34 has an annular packer 35 which engages the outer surface of the barrel 11 and the inner surface of the jacket 22 so as to provide a tight seal. This packer 35 is secured by suitable screws 36 to a body 37 of the plunger 34. The plunger 34 may also include one or more weights 38 which increase the pressure on the body 30.

The operation of the pump just described is as follows:

The plunger 18 is reciprocated in the barrel 11 and oil or other liquid is elevated to the 5 surface of the ground through the oil tube 17 in the customary manner. The fluid-pressure in the barrel 11 above the plunger 18 is communicated through the openings 29 to the upper end of the reservoir 26. This pressure is 10 applied to the body of abrasive excluding medium 30. In addition to this pressure there is the pressure which results from the weight of the plunger 34. It will be seen, therefore, that the pressure on the body of abrasive excluding 15 medium 30 is in excess of the fluid-pressure at the upper end of the plunger 18 an amount equal to that applied by the plunger 34. The abrasive excluding medium 30 is forced through the openings 28 at the 20 lower part of the reservoir 26 into the minute space which exists between the plunger 18 and the barrel 11. This medium flows in this space both upward and downward, exuding from the upper and lower ends of the 25 plunger 18. This medium being preferably in the form of a heavy lubricant lubricates the contacting surfaces of the barrel and plunger, and in addition to this absolutely prevents any sand carried by the liquid being 30 pumped from entering the space between these two parts. The pressure on the body 30 being in excess of the static pressure of the fluid at the upper part of the plunger 18 assures a slow but positive flow of abrasive 35 excluding medium through the space between the plunger and barrel.

In the form of the invention shown in Figs. 4 to 8 inclusive, there is a pump barrel 40, the lower end of which is connected to a foot 40 piece 41, this foot piece supporting a standing valve 42. Adapted to reciprocate in the barrel 40 is a pump plunger 43 having a traveling valve 44. The upper end of the plunger 43 extends above the upper end of 45 the barrel 40 and is connected to a string of sucker rods 45. The upper end of the barrel 40 is surrounded by a jacket 47 which is connected at 48 to the barrel. The upper end of this jacket 47 extends a considerable distance 50 above the upper end of the barrel 40 and is connected at 49 to an oil tube 50.

The jacket 47 provides a reservoir 52. The lower end of the reservoir 52 is connected to the space between the barrel and plunger by 55 a plurality of openings 53. That portion of the reservoir above the upper end of the barrel 40 is in communication with that part of the plunger 43 which projects above the barrel. Placed in the upper end of the reservoir 60 is a plunger 55 which presses downward on a body 56 of abrasive excluding medium which is preferably in the form of a heavy lubricant. The plunger 55 includes a lower packer 57 which engages the inner surface 65 of the jacket 47 and the external sur-

face of the plunger 43. The packer 57 is carried at the lower end of a head 58 of the plunger 55 from which head 58 there extends in an upward direction a tube 59. This tube 59 is of cylindrical cross-section, and the inner diameter is slightly larger than the external diameter of the plunger 43. The upper end of the tube 59 which comprises a part of the plunger 55 terminates below the upper end of the reservoir 52 and is centralized by a centralizing member having fins 60 which engage the inner surface of the jacket 47. 70 75

It will be seen that the upper part of the reservoir 52 above the packer 57 of the plunger 55 is in communication with the space above the plunger 43 and is subjected to the fluid-pressure at this point. This fluid-pressure plus the pressure resulting from the weight of the plunger 55 forces downward on the body 56 of abrasive excluding medium. The abrasive excluding medium is therefore forced through the openings 53 and into the space between the plunger and barrel of the pump. The sand excluding medium is also slowly forced upward between the plunger 43 and the packer 57. This insures that no sand or other abrasive will enter the contacting faces of either the pump or the barrel. 80 85 90

From the foregoing description it will be seen that even though the two forms of the invention differ slightly as to design, they both embody the important principle of the invention of supplying a sand excluding medium under pressure to the space between the plunger and barrel or to the outer surface of the plunger to prevent abrasives from getting onto the contacting moving parts; and also that important principle of the invention which provides for placing the sand excluding medium under greater pressure than the fluid-pressure at the upper end of the plunger so that there will be a slow but positive flow of sand excluding medium through the space between the plunger and the barrel. 95 100 105

We claim as our invention:

1. In a pump, the combination of: a barrel having a standing valve; a pump delivery tube; a plunger adapted to operate in said barrel, said plunger having a traveling valve discharging pumped fluid into said delivery tube; and means subjected to the pressure of the pumped fluid and supplying an additional pressure for forcing an abrasive excluding fluid medium through the space between the external surface of said plunger and the internal surface of the barrel with more pressure than the pressure of the fluid being pumped. 110 115 120

2. In a pump, the combination of: a barrel having a standing valve; a pump delivery tube; a plunger adapted to operate in said barrel, said plunger having a traveling valve discharging pumped fluid into said delivery tube; means forming a reservoir, said reservoir being in communication with the space 125 130

- between said plunger and said barrel and adapted to contain an abrasive excluding fluid medium; and means subjected to the pressure of the pumped fluid and supplying an additional pressure for placing a pressure on said abrasive excluding fluid medium in excess of the fluid-pressure at the top end of said plunger to feed said medium through said space.
3. In a pump, the combination of: a barrel having a standing valve; a pump delivery tube; a plunger adapted to operate in said barrel, said plunger having a traveling valve discharging pumped fluid into said delivery tube; means forming a reservoir, said reservoir being in communication with the space between said plunger and said barrel, and said reservoir being in communication with the delivery tube so that an abrasive excluding fluid medium in said reservoir will be subjected to the fluid-pressure of the pumped fluid to feed said medium through said space; and means in said reservoir for increasing the pressure on said abrasive excluding fluid medium so that said pressure will be in excess of the fluid-pressure at the top end of said plunger.
4. In a pump, the combination of: a barrel having a standing valve; a pump delivery tube; a plunger adapted to operate in said barrel, said plunger having a traveling valve discharging pumped fluid into said delivery tube; means forming a reservoir, said reservoir being in communication with the space between said plunger and said barrel, and said reservoir being in communication with the delivery tube so that an abrasive excluding fluid medium in said reservoir will be subjected to the fluid-pressure of the pumped fluid; and a weighted piston in said reservoir for increasing the pressure on said abrasive excluding fluid medium so that said pressure will be sufficient to cause said abrasive excluding fluid medium to flow slowly but positively through said space.
5. In a pump, the combination of: a barrel having a standing valve; a pump delivery tube; a plunger adapted to operate in said barrel, said plunger having a traveling valve discharging pumped fluid into said delivery tube; means forming a reservoir, said reservoir being in communication with the space between said plunger and said barrel, and said reservoir being in communication with the delivery tube so that an abrasive excluding fluid medium in said reservoir will be subjected to the fluid-pressure of the pumped fluid to feed said medium through said space; and means for increasing the pressure on said abrasive excluding fluid medium so that said pressure will be in excess of the fluid-pressure at the top end of said plunger.
6. In a pump, the combination of: a barrel having a standing valve; a pump delivery tube; a plunger adapted to operate in said barrel, said plunger having a traveling valve discharging pumped fluid into said delivery tube; means forming a reservoir, said reservoir being in communication with the space between said plunger and said barrel, and said reservoir being in communication with the delivery tube so that an abrasive excluding fluid medium in said reservoir will be subjected to the fluid-pressure of the pumped fluid to feed said medium through said space; and a piston in said reservoir above said abrasive excluding fluid medium for increasing the pressure on said abrasive excluding fluid medium so that said pressure will be in excess of the fluid-pressure at the top end of said plunger.
7. In a pump, the combination of: a barrel having a standing valve; a pump delivery tube; a plunger adapted to operate in said barrel, said plunger having a traveling valve discharging pumped fluid into said delivery tube; means forming a reservoir, said reservoir being in communication with the space between said plunger and said barrel, and said reservoir being in communication with the delivery tube so that an abrasive excluding fluid medium in said reservoir will be subjected to the fluid-pressure of the pumped fluid; and a weighted piston in said reservoir for increasing the pressure on said abrasive excluding fluid medium so that said pressure will be sufficient to cause said abrasive excluding fluid medium to flow slowly but positively through said space.
8. In a pump, the combination of: a barrel having a standing valve; a pump delivery tube; a plunger adapted to operate in said barrel, said plunger having a traveling valve discharging pumped fluid into said delivery tube; means forming a reservoir, said reservoir being in communication with the space between said plunger and said barrel, and said reservoir being in communication with the delivery tube so that an abrasive excluding fluid medium in said reservoir will be subjected to the fluid-pressure of the pumped fluid; and a weighted piston for increasing the pressure on said abrasive excluding fluid medium so that said pressure will be sufficient to cause said abrasive excluding fluid medium to flow slowly but positively through said space.
9. In a pump, the combination of: a barrel having a standing valve; a pump delivery tube; a plunger adapted to operate in said barrel, said plunger having a traveling valve discharging pumped fluid into said delivery tube; means forming a reservoir, said reservoir being in communication with the space between said plunger and said barrel, and said reservoir being in communication with the delivery tube so that an abrasive excluding fluid medium in said reservoir will be subjected to the fluid-pressure of the pumped fluid; and a weighted, substantially fluid-

5 tight piston in said reservoir above said abrasive excluding fluid medium for increasing the pressure on said abrasive excluding fluid medium so that said pressure will be sufficient to cause said abrasive excluding fluid medium to flow slowly but positively through said space.

10 10. In a pump, the combination of: a barrel having a standing valve; a pump delivery tube; a plunger adapted to operate in said barrel, said plunger having a traveling valve discharging pumped fluid into said delivery tube, the upper end of said plunger extending above said barrel; walls forming a reser-

15 15. said reservoir surrounding the upper end of said plunger and communicating with said delivery tube, said reservoir having an abrasive excluding fluid medium therein; and means subjected to the pressure of the 20 pumped fluid and supplying an additional pressure for placing a pressure on said abrasive excluding fluid medium in excess of the fluid-pressure at the top end of said plunger to feed said fluid medium through the space 25 between said plunger and said barrel.

11. In a pump, the combination of: a barrel having a standing valve; a pump delivery tube; a plunger adapted to operate in said barrel, said plunger having a traveling valve 30 discharging pumped fluid into said delivery tube, the upper end of said plunger extending above said barrel; walls forming a reservoir, said reservoir surrounding the upper end of said plunger, said reservoir having 35 an abrasive excluding fluid medium therein, and said reservoir being in communication with the delivery tube so that said abrasive excluding fluid medium in said reservoir will be subjected to the fluid-pressure 40 of the pumped fluid to feed said fluid medium through the space between said plunger and said barrel; and means in said reservoir for increasing the pressure on said abrasive excluding fluid medium so that said pressure 45 will be in excess of the fluid-pressure at the top end of said plunger.

12. In a pump, the combination of: a barrel having a standing valve; a pump delivery tube; a plunger adapted to operate in said 50 barrel, said plunger having a traveling valve discharging pumped fluid into said delivery tube, the upper end of said plunger extending above said barrel; walls forming a reservoir, said reservoir surrounding the upper 55 end of said plunger and communicating with said delivery tube, said reservoir having an abrasive excluding fluid medium therein; and a substantially fluid-tight piston subjected to the pressure of the pumped fluid 60 and supplying an additional pressure for placing a pressure on said abrasive excluding fluid medium sufficient to cause said abrasive excluding fluid medium to flow slowly but positively through said space.

65 13. In a pump, the combination of: a bar-

rel having a standing valve; a pump delivery tube communicating with said barrel; a plunger having a traveling valve discharging pumped fluid into said delivery tube; means forming a reservoir communicating with the space between said plunger and said barrel and with said delivery tube so that an abrasive excluding fluid medium in said reservoir will be subjected to the pressure of the pumped fluid to feed said medium through said space; and means in said reservoir adapted to follow said medium and prevent contamination thereof by the pumped fluid.

14. In a pump, the combination of: a barrel having a standing valve; a pump delivery tube communicating with said barrel; a plunger having a traveling valve discharging pumped fluid into said delivery tube; means forming a reservoir communicating with the space between said plunger and said barrel and with said delivery tube so that an abrasive excluding fluid medium in said reservoir will be subjected to the pressure of the pumped fluid to feed said medium through said space; means in said reservoir adapted to follow said medium and prevent contamination thereof by the pumped fluid; and means for applying an additional pressure to said fluid medium.

In testimony whereof, we have hereunto set our hands at Los Angeles, California, this 11th day of July, 1927.

ROSCOE W. STEPHENS.
CHARLES E. WILCOX.
